DESIGN FOR A PIPE HOLDER OR SIMILAR ARTICLE

Eugene J. Rich, Lawrence, N. Y.

Application November 8, 1945, Serial No. 123,574

Term of patent 14 years

(Cl. D85—8)

To all whom it may concern:

Be it known that I, Eugene J. Rich, a citizen of the United States, residing at 21 Auerbach Lane, Lawrence, county of Nassau, State of New York, have invented a new, original, and ornamental Design for a Pipe Holder or Similar Article, of which the following is a specification, reference being had to the accompanying drawings, forming part thereof.

In the drawings:

Fig. 1 is a front perspective view of a pipe holder embodying my new design.

Fig. 2 is a side view of the display.

Fig. 3 is a rear perspective view of the display.

I claim:

The ornamental design for a pipe holder or similar article, substantially as shown.

EUGENE J. RICH.
